Inventor:

Hans Bach

United States Patent Office.

HANS BACH, OF PATERSON, NEW JERSEY.

Design No. 3,567, dated July 6, 1869.

DESIGN FOR A PHOTOGRAPHIC PORTRAIT-HOLDER.

The Schedule referred to in these Letters Patent and making part of the same.

To all whom it may concern :

Be it known that I, HANS BACH, of Paterson, Passaic county, New Jersey, have invented a new and original Design for Photographic Groups; and I do hereby declare that the following is a full, clear, and exact description thereof, which will enable others skilled in the art to make and use the same, reference being had to the accompanying drawing, forming part of this specification.

The drawing represents a face view illustrating my design.

This invention relates to a new design for the backgrounds of photographic portraits, groups, &c., and has for its object to beautify the same.

The invention consists in the arrangement of flowers and buds, or representations thereof, in the form of a bouquet, shown in the drawing.

The stems of the flowers forming the bouquet are secured together by a ribbon formed into a bow.

The full-blown flowers (shown, two in red, and one in violet color,) are designed to envelop portraits or other pictures of persons somewhat advanced in years, or at least of mature age, while the buds shown immediately above, are intended to receive pictures of young persons.

I arrange leaves about the aforesaid buds and flowers, as shown in the drawing.

Having thus described my invention,

What I claim as new, and desire to secure by Letters Patent, is—

The design for photographic portraits and groups herein described.

HANS BACH.
